UNITED STATES PATENT OFFICE.

CHARLES S. OVERTON, OF BALTIMORE, MARYLAND.

DESIGN FOR A CASING FOR COMBINATION STOP AND PARKING LIGHTS FOR AUTOMOBILES.

Application filed February 7, 1924. Serial No. 8,567. Term of patent 3½ years.

To all whom it may concern:

Be it known that I, CHARLES S. OVERTON, a citizen of the United States, residing at Baltimore, in the State of Maryland, have invented a new, original, and ornamental Design for a Casing for a Combination Stop and Parking Light for Automobiles, of which the following is a specification, reference being had to the accompanying drawing, forming a part thereof, and of which:—

Fig. 1 is an elevation of one side thereof;
Fig. 2 is a plan view of the casing;
Fig. 3 is a rear view of the casing; and
Fig. 4 is a front view of the casing.
I claim:

The ornamental design for a casing for combination stop and parking lights for automobiles, as shown.

CHARLES S. OVERTON.
